MACHINE FOR CONCENTRATING ORES AND AMALGAMATING GOLD ORES

Sydney Walter Lack, Waverley, near Sydney, New South Wales, Australia

Application January 13, 1934, Serial No. 706,480
In Australia April 27, 1933

6 Claims. (Cl. 209—199)

This invention relates to ore concentrating machines, usable also as amalgamators for gold bearing ore, of the kind in which a slurry or pulp of milled ore in water is caused to pass through a rotating vessel in which it is subjected to centrifugal action in water in circulation through such vessel, thereby to effect separation of light density material from heavy density material, for elimination of the light material in the water flow and retention of the heavy material in the vessel. For amalgamation, mercury is introduced while the machine is in rotation and is held spread on the interior surface of the vessel by centrifugal action; in this case the amalgam is ultimately removed from the bowl with concentrates collected therein.

The machine in which the present invention consists comprises an outer vessel of stepped inverted conical section with annular flanges of progressively increasing diameter in stepped order around its interior face, said outer vessel mounted for rotation on an axial shaft disposed vertically; a conical double walled vessel within said outer vessel mounted for rotation on a vertical shaft coaxially with the outer vessel; horizontal swing-blades carried by the interior vessel, and operating in the annuli intermediate the annular flanges on the interior face of the wall of the outer vessel; and means for applying rotation at differential speeds to the respective vessels. The swing blades throw outward by centrifugal action and carve the ore pulp in the annular spaces between the flanges in the outer vessel and keep it agitated and in a free flowing state while the heaviest particles are separated by centrifugal action and deposited upon the wall of the outer vessel. The respective vessels are driven at differential peripheral velocities.

A free flowing pulp of ore and water is poured into the wall space in the inner vessel in a continuous stream which flows radially outward at the bottom of said vessel into an annular bottom space in the outer vessel. The pulp moves thence by centrifugal action upwardly in the outer vessel against its wall, and in its course it is subjected to agitation by the carving action of the swing blades, whereby any lumps contained in it are broken and the pulp is kept in a lively flowing state; the heavier particles of mineral matter which were contained in the pulp are retained in the annuli between the flanges and the water borne tailings flow upwards over the flanges and ultimately pass out through vents in a rim flange at the top of the outer vessel. In

the case of use of the machine as an amalgamator, mercury is introduced and spreads over the wall of the outer vessel and is retained there until a large tonnage of pulp has been treated. The gold in the pulp contacts intimately with the mercury and is amalgamated therewith.

A machine embodying the invention is illustrated in vertical section in the accompanying drawing.

10 is a bed plate, and 11 and 12 are bearings for drive shafts which are bevel geared (13—14) to the centre shaft 15 which carries the inner cone vessel and the sleeve shaft 16 which carries the concentrator vessel. 17 are bearings in the pillar portion 18 of the bed, 19 is a foot-step bearing, and 21 a collar bearing on the shaft 15 which carries the foot of the sleeve shaft 16. The mechanical design of the drive arrangement is subject to modification and it does not in itself form part of the invention. The outer concentrator vessel 23 is of inverted truncated cone shape and it has a re-entrant conical hub portion 24 which projects upwardly within the cone 38 of the inner vessel 27 and is keyed or otherwise fixed (22) to the sleeve shaft 16; the sides 25 of the outer vessel are stepped (25) and annular flanges 26 are formed on its inner face at the top of each stepping. These flanges (26) are also stepped, that is to say, their respective diametral measurements are increased progressively according to their distance from the bottom to the top of the vessel. It is advantageous to provide intermediate shallow flanges 51 between the stepped flanges, and it is also advantageous to perforate the stepped flanges near the wall line (55), provided that the perforations 50 are not brought quite close to the wall of the vessel. The inner vessel 27 is conical and has a re-entrant cone base 28, the top of which is fixed to the top end of the shaft 15; this cone forms with the outer wall of said vessel an annular passage through which the pulp flows into the bottom of the outer vessel 23. The feed of pulp passes (while the machine is in operation) down through the annulus about the cone base 28 and flows radially outward at the foot of the annulus space 29 into the bottom of the outer vessel 23; thence it ascends in that vessel by reason of centrifugal action produced by the rotation of the outer vessel; practically none of it leaks through the discharge vents 43. 30 are swing beater blades hung freely on vertical pintle spindles 31 which are carried on the periphery of the inner conical vessel 27; the blades 30 are located intermediate the flanges 26 55

and operate to slash and agitate material which tends to congregate between these flanges and thereby maintain the portions of it which can be water borne in a flowing agitated condition so that they will pass upwardly in the water scour. 5 32 is a cover ring on the rim of the outer vessel, and 33 are vents therein for release of the ascending tail water and tailings.

43 are vents for releasing the saved concentrates; they remain permanently open. When 10 the machine becomes charged up with concentrates, it is stopped; the concentrates (and/or amalgam) sluice out through these vents by gravity when the speed is sufficiently reduced. Any 15 residuum sticking in the vessel may be washed out. The concentrates are found collected in the horizontal annuli between the flanges 26.

The drive is arranged to effect rotation of the 20 respective vessels at different speeds, and the speeds are regulated appropriately to the nature of the ore and the density of the pulp to effect the desired degree of separation of the lighter from the heavier constituents of the ore. In the 25 case of a machine in which the rim diameter of the outer vessel is about 30 inches, operating on wash dirt containing fine gold, the outer vessel is rotated at about 250 revolutions per minute and the inner cone which carries the agitator blades 30 is rotated at about 320 revolutions per minute.

30 Fine grinding of the ore is essential in nearly all cases to ensure a free flowing condition of the pulp, which consists of ore carried in suspension in the water.

35 What I claim as my invention and desire to secure by Letters Patent is:—

1. An ore separating machine comprising a vertical outer inverted conical vessel with annular internal flanges on its wall and discharge 40 vents in the bottom of it, said flanges of progressively increasing diameters in ascending order, an inner erect conical vessel concentrically mounted within said outer vessel and communicating therewith at the foot of it, means for applying rotation about a common vertical axis at 45 differential speeds to said vessels, and swing blades hung on pintles carried on said inner vessel at positions intermediate the flanges on the inner side of the outer vessel.

50 2. An ore separating machine comprising a vertical inverted truncated conical vessel with annular internal flanges of progressively increasing diameter in ascending order, a concentrate discharge vent in the bottom of said vessel, an inner erect conical vessel concentrically disposed 55 within said outer vessel, passageways at the foot of said inner vessel adapted for passing flowing pulp therethrough into the bottom of said outer vessel, freely swinging members carried on the outer wall of said inner vessel said members adapted to throw outward by centrifugal action 60 and slash and agitate pulp ascending in said outer vessel, and means for rotating said inner vessel and said outer vessel at different peripheral velocities thereby to subject the pulp to centrifugal separation while it is maintained in agitated condition.

3. An ore separating machine as claimed in claim 2 wherein the radially disposed members carried on the inner vessel extend into the annuli between the annular flanges on the inner surface of the outer vessel without touching any part of the outer vessel. 5

4. An ore separating machine comprising an inverted truncated conical vessel with internal 10 annular flanges in stepped order on its inner face, concentrate discharge vents in the bottom of said vessel, an interior flange on the rim of said vessel, a conical member concentrically disposed in said vessel, passageways in said member adapted for passing pulp therethrough into the bottom of said vessel, swing blades carried on said member adapted to subdivide and agitate pulp ascending in said vessel, and means for rotating said vessel and said member at different peripheral velocities thereby to subject the pulp to centrifugal separation while maintaining it in an agitated condition. 15

5. An ore separating machine comprising a 20 vertically disposed hollow vessel of truncated conical shape having internal annular flanges in stepped diameters on its wall at spaced intervals, a rim lip on its open top end and discharge vents in the bottom of it, a re-entrant cone hub on the bottom of said vessel carrying it on an axial shaft, a conical interior vessel with open top and with a re-entrant hub on the bottom of it fixed to a vertical shaft concentric with the aforesaid shaft, passageways from the 25 foot of the annulus between said interior vessel and its hub adapted for passing pulp from the interior of said vessel into the foot of said outer vessel, vertical spindles carried on the exterior side of said conical interior vessel, swing blades 30 on said spindles positioned to locate in the spacings between the spaced flanges on the wall of said outer vessel, and means for applying differential rotation to said spindles.

6. An ore separating machine comprising an 45 exterior inverted conical vessel with annular internal flanges at spaced intervals on its wall, said flanges of progressively increasing diameter in ascending order, an inward flange on its rim, discharge vents in the bottom of it, an interior 50 erect conical annular vessel disposed concentrically within said exterior vessel, an annular passage between the foot of said inner vessel and the bottom of said outer vessel, swinging members carried on the external part of the inner 55 vessel, said members spaced to locate in the annuli in the outer vessel intermediate the annular internal flanges therein without touching the outer vessel, and adapted by reason of differential speeds of rotation of the vessels to slice and 60 agitate pulp which is in flowing progression upwardly in said outer vessel, and means for applying rotation at differential speeds to said vessel.
